UNITED STATES PATENT OFFICE.

JONATHAN D. POWELL, OF LYNN, MICHIGAN.

SILO.

No. 833,242.

Specification of Letters Patent.

Patented Oct. 16, 1906.

Application filed May 10, 1906. Serial No. 316,184.

To all whom it may concern:

Be it known that I, JONATHAN D. POWELL, a citizen of the United States, residing at Lynn, in the county of St. Clair and State of Michigan, have invented a new and useful Silo, of which the following is a specification.

This invention relates to silos; and it is an improvement on the device of this class for which application for Letters Patent of the United States was filed by myself on the 14th day of June, 1905, Serial No. 265,211.

Among the objects of the present invention are to simplify and improve the construction of the door of the silo, to facilitate the opening and closing of the door, to provide an improved construction under which the door is composed of two minor sections having adjacent beveled edges adapted for slideable engagement in combination with connecting means, whereby the door-sections may be manipulated in such a manner as to expand the door laterally and bring the edges thereof into forcible contact with the door-posts, so as to insure tight joints.

Another object of the invention is to provide an improved construction under which the hoops of the silo are utilized in connection with wedges to secure the doors against the pressure of the contents of the silo.

Still further objects of the invention are to simplify and improve the construction and operation of the device as a whole.

With these and other ends in view, which will readily appear as the nature of the invention is better understood, the same consists in the improved construction and novel arrangement and combination of parts, which will be hereinafter fully described, and particularly pointed out in the claims.

In the accompanying drawings has been illustrated a simple and preferred form of the invention, it being, however, understood that no limitation is necessarily made to the precise structural details therein exhibited, but that changes, alterations, and modifications within the scope of the invention may be made when desired.

In the drawings, Figure 1 is a front elevation of a portion of a silo constructed in accordance with the principles of the invention. Fig. 2 is a horizontal sectional view taken on the plane indicated by the line 2 2 in Fig. 1. Fig. 3 is a horizontal sectional detail view taken on substantially the same plane as Fig. 2, but showing one of the door-sections partly open. Fig. 4 is a vertical sec-

tional detail view taken on the plane indicated by the line 4 4 in Fig. 1. Fig. 5 is a sectional detail view taken on the plane indicated by the line 5 5 in Fig. 1. Fig. 6 is a detail view of one of the door-braces detached. Fig. 7 is a sectional detail view, on a larger scale, showing the free edge of one of the door-sections in the position which it occupies just before closing.

Corresponding parts in the several figures are indicated throughout by similar characters of reference.

The silo is constructed in the ordinary manner of matched staves 1 1, bound together by hoops 2 2, each of which, as seen in Figs. 1 and 2, may be made up of a plurality of sections connected at their ends by means of clips or connecting members 3, with which the ends of the hoops or hoop members may be connected in any convenient and well-known manner. A doorway is formed in the silo by omitting two or more staves. The staves adjacent to the doorway are specially designated 1^a and 1^b, and these staves will be regarded as constituting the door-posts.

The door of the silo, which extends from the top to the bottom, is composed of a plurality of independent sections 5 5, each of said sections being composed of two minor sections 5 and 6. The section or member 5 is made of a width to fill the greater part of the door-opening, and said member may be constructed of any desired number of pieces of matched lumber connected securely together by means of horizontally-disposed transverse brace-bars 7 7, which are preferably connected with the individual strips 8 8, of which the member 5 may be composed, by means of bolts 9 extending through slots 10' in the brace member. By this construction a shrinkage in the lumber of which the door member is composed may be compensated for by loosening the bolts 9, when the parts may be brought closely together, so as to re-establish a tight joint.

The minor sections or members 5 and 6 of each door-section are provided with contacting beveled edges, and the members 6 are provided with brace-blocks 10, having beveled ends abutting upon the correspondingly-beveled ends of the braces 7. The latter are provided with washer-plates 11, projecting beyond their beveled ends and having apertures for the passage of bolts 12, which extend obliquely through the members 6 and through the brace-blocks 10. These bolts

serve to so connect the members 6 with the members 5 that by loosening the nuts 13 upon said bolts the beveled edges of the door members will admit of a relative sliding movement of the members, whereby the distant edges of said members will move toward each other or the distance between said edges will be restored, while by tightening the said nuts the opposite movement will result and the distance between the outer or distant edges of the door members will be increased. The members 5 of the door-sections are connected with the stave constituting the door-post 1^a by means of hinges 14. The brace-blocks 10 of the door members 6 are extended beyond the outer edges of said door members, so as to overlap the staves constituting the door-post 1^b.

It is obvious that in the construction of this device the door-sections S will be made of dimensions calculated to fit extremely tightly in the door-opening. When the silo is empty and is ready to be filled, all of the door-sections will be tightly closed, as will be readily understood. Any one or more of the door-sections may be opened to afford access to the interior of the silo by loosening the nuts 13 of the connecting-bolts 12 of the section that is to be opened, thus permitting the door member 5 to move outward at its free edge until the lateral pressure against the proximate door member 6 is reduced sufficiently to enable it to swing clear of the door-opening, when the door may be swung open, thus enabling a portion of the contents of the silo to be removed. When this has been done, the door may be closed by swinging it shut until the brace-blocks 10 of the member 5 abut upon the door-post 1^b. Then by tightening the nuts 13 the free edge of the door member 5 will be forced in an inward direction, thus exerting lateral pressure upon the member 5 until an absolutely tight closure has been effected.

The upper and lower edges of the door-sections are slightly beveled, as will be seen at 15 in Figs. 4 and 5, said beveled edges co-operating to form V-shaped grooves, in which packing material of any kind—such as cotton, hemp, ensilage, or other material—may be packed from the interior of the silo when the latter is being filled. Absolutely tight joints may thus be made without obstructing or interfering with the subsequent opening of the doors.

The door-sections S are preferably made of such height as to extend between proximate hoops 2-2 of the silo, one such hoop being preferably disposed at the meeting joint of proximate door-sections. For additional security wedges, as 16, are driven between the hoops and the faces of the door-sections. The hoops being disposed normally in alignment with the joints or intersections of the door-sections would to some extent obstruct

the opening of the latter by contacting with their upper and lower edges. Hence when a door-section is to be opened it becomes necessary not only to remove the wedges 16, but also to slightly displace the proximate hoops 7^a 2 sufficiently to enable the door-sections to swing clear of the latter. To enable such displacement of the hoops to be readily performed, the several staves of the silo, as well as the door-sections, are provided with wear-plates 17, supporting the hoops and preventing them from sinking or becoming embedded in the wood of the staves and the door-sections. The hoops are usually constructed on round iron, as shown in the drawings; but this is non-essential.

From the foregoing description, taken in connection with the drawings hereto annexed, the operation and advantages of this invention will be readily understood by those skilled in the art to which it appertains.

A silo embodying my present improvements may be manufactured, installed, and maintained at a moderate expense. Convenient access is afforded to any portion of the silo, so that as the contents of the latter are gradually removed a door may be opened at the level of the contents.

The gist of the invention resides in the facility with which the doors may not only be opened but also restored to an absolutely tight condition, since by simply manipulating the nuts 13 the doors may be easily and tightly closed against the powerful pressure existing within the silo.

Having thus described the invention, what is claimed is—

1. A silo having a door-opening, a door-section hinged only along one edge of the opening and comprising members having beveled contacting edges, and means whereby said members may be moved together to exert lateral pressure.

2. A silo having a door-opening and staves constituting door-posts, a door-section comprising members having beveled contacting edges, brace-blocks upon one member overlapping the proximate door-post, and means for moving the members together to exert lateral pressure upon the door-posts.

3. In a silo, staves constituting door-posts, a door-section including minor sections one of which is hinged upon one of the door-posts, said minor sections or members having beveled contacting edges, and means for supporting one member on the other and whereby said members may be moved together to exert lateral pressure upon the door-posts.

4. In a silo, a door-section including minor sections or members having beveled contacting edges, bevel-ended brace-bars upon one member, bevel-ended brace-blocks upon the other member, washer-plates secured upon and projecting beyond the beveled ends of the brace-bars of the first member, connecting

its extending through the second member and through the brace-blocks connected therewith and engaging the washer-plates, and locking-nuts.

5. In a silo, a door-section including two minor sections or members; one of said members being composed of a plurality of pieces of matched lumber adjustably connected by transverse brace-bars having slots and bolts extending through said slots, and said minor sections having beveled contacting edges; in combination with washer-plates secured upon and extending beyond the transverse connecting-bars of the one section, and bolts connecting the other section with said washer-plates.

6. In a silo, a laterally-expansible door comprising two loosely-connected members having beveled contacting edges adjustably held in engagement.

7. In a silo, a laterally-expansible door

mounted to swing on one axis and comprising two loosely-connected members having beveled contacting edges, and means for moving one of said members slidably upon the other and for securing it at various adjustments.

8. In a silo, a laterally-expansible door comprising two loosely-connected members; one of said members being hingedly supported and the other member being provided with a laterally-extending stop; said members being provided with beveled contacting edges.

In testimony that I claim the foregoing as my own I have hereto affixed my signature in the presence of two witnesses.

JONATHAN D. POWELL.
